J. W. COAST, JR.
ART OF CRACKING HYDROCARBONS.
APPLICATION FILED SEPT. 27, 1917.

1,355,312.

Patented Oct. 12, 1920.

UNITED STATES PATENT OFFICE.

JOHN W. COAST, JR., OF TULSA, OKLAHOMA, ASSIGNOR TO THE PROCESS COMPANY, OF TULSA, OKLAHOMA, A CORPORATION OF MARYLAND.

ART OF CRACKING HYDROCARBONS.

1,355,312.

Specification of Letters Patent. Patented Oct. 12, 1920.

Application filed September 27, 1917. Serial No. 193,456.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in Art of Cracking Hydrocarbons, of which the following is a full, clear, and exact description, references being had to the accompanying 10 drawing, forming a part of this specification.

This invention relates to improvements in the art of cracking hydrocarbons, the main object being to generally improve this art by 15 providing a safe, economical and highly efficient method of treating high boiling point hydrocarbons to obtain a more volatile product known as gasoline, or crude gasoline.

20 More specifically stated, an object of the invention is to protect cracking stills from the injurious effects of free carbon and tarry substances known in the art as coke and coke-forming matter. By positively eliminating the danger and minimizing the labor and trouble usually due to the formation of 25 "coke" in cracking stills, the cracking operations can be carried on continuously for a much longer period of time, without cooling the stills and without removing the residues. A great saving of time and fuel is effected by operating the stills in this manner. The method of circulating and collecting the coke-forming matter overcomes the 30 danger of overheating and rupturing the stills, thereby very materially increasing the life of the stills and reducing the cost of repairs to a minimum. This coke-forming matter is not a good conductor of heat, and 35 in the ordinary cracking stills it accumulates between the fire and the oil, thus preventing the free transmission of heat to the oil. Under these conditions, the still becomes overheated, and fuel is dissipated or wasted in 40 heating the coke, instead of being utilized 45 as an efficient heating medium for the oil.

Another object of the invention is to facilitate the cleaning of the still by causing coke-forming matter to accumulate in receptacles 50 from which it can be easily removed.

Another object is to generally increase the efficiency of the apparatus by forcibly circulating the oil from a still through a heating coil and back, thereby further economizing 55 in the use of fuel, maintaining all of the oil

at a desirable high temperature, and enabling the temperature of all of the oil to be raised quickly at the beginning of the operation.

A further object is to increase the yield of 60 low boiling point hydrocarbons by subjecting the oil to treatment in two different feeding devices, as will be hereinafter pointed out. The pressure and temperature of the contents of the still are preferably 65 different from the pressure and temperature of the coil, and a stream of the oil undergoing distillation is circulated back and forth, from the still and through the coil.

In the preferred form of the invention, 70 all of the foregoing advantages are obtained by continually circulating a stream of oil from a large cylindrical cracking still, through a pipe coil and then back to the cylindrical cracking still, at the same time 75 separating coke-forming matter from the circulating oil. The contents of the pipe coil may be maintained at a higher temperature and under a higher pressure than the cylindrical still. It may be noted that 80 the relatively small pipe of a coil will withstand a higher pressure than a large cylindrical still. In treating some oils, the pipe coil is maintained at a relatively high temperature and the pressure is regulated so 85 as to prevent vaporization therein. The heavy hydrocarbons are thus subjected to the desired degree of heat, and thereafter permitted to vaporize at a lower temperature 90 in the large still, where the pressure is low enough to obtain this result. However, both the still and the pipe are preferably maintained under pressure, and at a cracking temperature. If desired, a substantially 95 uniform temperature and pressure may be maintained throughout the apparatus.

Figure I is a diagrammatical view of a cracking apparatus adapted for use in carrying out the new method.

Fig. II is an enlarged vertical section of 100 one of the strainers, or filters, whereby coke-forming matter is separated from the circulating oil.

In the apparatus shown to illustrate the invention, a large cylindrical cracking still 105 1 is arranged above a heating chamber 2 and connected by means of a vapor pipe 3, to an air cooled reflux condenser 4. 5 designates a vapor pipe leading from the reflux condenser 4 to a main condensing coil 6 110

from which the low boiling point product is recovered. The condensing coil 6 is preferably arranged in a water tank 7.

8 designates a heating pipe, or cracking coil, preferably consisting of a long coil of relatively small pipe arranged in a heating chamber or furnace 9. An intake pipe 10, leading from the lower end of the coil 8, passes through an end wall of the cylindrical still 1 and is connected to a filter A. 11 designates a pipe section arranged in the lower portion of the cylindrical still 1 and connected to a rotary pump 12. A pipe section 13 leads from the pump to the filter A. A power shaft 14, passing through a stuffing box 15 at one end of the cylindrical still, may be rotated to actuate the pump 12. A pinion 16 fixed to the inner end of shaft 14, meshes with an operating wheel 17 on the pump, and this shaft 14 may be rotated by transmitting power to a wheel 18 at the exterior of the still.

The pipe coil 8 is provided with a discharge pipe 19 passing through an end of the cylindrical still and connected to a filter A', the latter being provided with a discharge pipe 20.

The cracking elements may be heated in any suitable manner, and the temperature of each still may be regulated independently of the other. In the structure shown, an oil burner 21 is arranged in the heating chamber 9, and the temperature of the pipe coil may be regulated by adjusting a valve 30 adjacent to the burner 21. The bottom of the large cylindrical still may be heated by a flame discharged from an oil burner 23, and the temperature may be regulated by adjusting a valve 24. To avoid the heat losses usually incurred by discharging hot gases and products of combustion from a heating chamber, a flue 25 leads from the heating chamber 9 to the heating chamber 2. The hot fluid passing from the chamber 9, flows over a baffle 26, then downwardly through the flue 25 to the heating chamber 21 below the still 1. A flue 27 leads from the heating chamber 2. 28 designates a by-pass formed below the heating chamber 2 to place the flue 25 in communication with the flue 27. A damper 29 may occupy the position shown in Fig. I to close communication between the flue 25 and the by-pass 28, and said damper may be adjusted to the position shown by dotted lines, so as to prevent the hot gases from flowing through the heating chamber 2.

The filters, or strainers, A and A' may be made exactly alike, each preferably comprising a screen 30 (Fig. II) arranged in a housing 31 wherein the coke-forming matter is separated from the oil. Each filter, or strainer, may also include a layer of mineral wool 32 arranged above the screen 30, and a layer of fullers' earth 33 between the

mineral wool and the top wall of the housing 31. This top wall may be easily removed for the purpose of removing accumulations of coke-forming matter from the filter.

While the oil is undergoing distillation, the rotary pump 12 is operated continually, thereby drawing oil and coke-forming matter through the perforations in the intake pipe 11 near the hot still bottom, the stream of oil and coke-forming matter being drawn to the pump 12, and forced through the pipe 13 to the filter A. The free carbon, or coke-forming matter, accumulates in the filter A, and the filtered oil is constantly discharged through the pipe 10 to the intake end of the pipe coil 8. A stream of oil is thus taken from the relatively large body in the cylindrical still 1, and forced through the pipe coil 8 from which it is discharged through the pipe 19, filter A' and discharge pipe 20. The stream of oil is forced through the pipe coil at a high velocity, so as to carry the coke-forming matter to the filter A', the filtered oil being discharged through the pipe 20 to the main body of oil in the large still. By circulating and filtering a stream of oil as herein shown, coke-forming matter is constantly drawn from the lower portion of the large still 1 and deposited in the filter A, where it will not in any way interfere with the transmission of heat to the oil.

It is also an advantage to filter the oil before discharging it into the pipe coil. The usual method of cracking hydrocarbons in pipe coils, consists in forcing a fresh charge of unheated oil into the hot coil of pipe, without in any way removing coke-forming matter from the oil. As a result, the coke or carbon accumulates in the small pipe, and at some point or points the coil soon becomes clogged with the coke or carbon, and it is then usually necessary to discontinue the cracking operation for the purpose of removing the coke from the pipe. There is also danger of overheating the pipe at the coke deposits. Therefore, one of the desirable features of the present invention consists in subjecting the oil to a cracking operation in the large cylindrical still, forcing a stream of the hot oil through the pipe, and at the same time separating free carbon or coke-forming matter from the oil before it reaches the pipe. This, of course, will not entirely prevent the formation of coke or carbon in the pipe, so the oil is again filtered in the filter A' before it is returned to the main body in the large still.

It will now be understood that the present invention overcomes, or materially reduces, the danger and expense due to the presence of carbon or coke in the still, at the same time avoiding the loss of heat usually due to accumulations of coke between the fire and the oil. The circulation of the oil also in-

creases the efficiency of the heating elements. Another important feature consists in the treatment of the same body of oil in a large cracking still and also in a pipe. Some oils, or some constituents of the heavy hydrocarbon oil, will not respond readily to the cracking operation which takes place in only one of the cracking devices. By repeatedly subjecting the oil to the conditions existing in both devices, a more effective cracking operation is obtained, and the yield of low boiling point liquid is greatly increased.

Owing to the manner in which the oil is circulated, also to the removal of coke from the walls of the stills, the apparatus can be operated continuously for a considerable period of time, and a fresh charge of oil can be occasionally introduced into the system, by means of a pump 30' and a pipe 31' leading from the pump to the pipe 10.

The apparatus herein shown is particularly adapted for use in cracking high boiling point products of distillation, such, for example, as distillates, or residues, resulting from the distillation of crude petroleum. By regulating a valve 32', in the vapor pipe 5, any desired pressure may be obtained in the large cylindrical still 1. The pressure in the pipe may be regulated by adjusting a valve 33' in the discharge pipe 19. The pressure in the large still is preferably greater than 50 pounds per square inch, for example, about 80 pounds per square inch, and the temperature of the contents of the large still preferably ranges from about 600° F. to 800° F. The low boiling point vapors passing from the liquid, flow through the vapor pipe 3 and reflux condenser 4 to the pipe 5 leading to the main condenser 6 from which the low boiling point product is recovered.

The two different stills herein shown are preferably maintained at different temperatures and under different pressures, the pressure and temperature in the pipe still being preferably higher than the pressure and temperature in the larger still. The small pipe will withstand a relatively high pressure and a relatively high temperature. By regulating the valve 33', any desired relatively high pressure, for example, 150 pounds per square inch, can be maintained in the pipe still, while the valve 32' in the vapor pipe 5 is regulated to maintain a lower pressure, for example, 80 pounds per square inch, in the large cylindrical still. Although the temperature of the pipe coil is relatively high, vaporization of the oil therein can be prevented by the relatively high pressure, and when the oil is discharged through the pipe 19 to the large still, its lighter constituents are permitted to vaporize under the lower degree of pressure in the large still. Many of the heavy fractions which do not respond to the ordinary cracking treatment

may be successfully cracked when subjected to the high pressure and the high temperature existing in the pipe coil. Obviously, such treatment increases the yield of low boiling point fractions.

Since the large body of oil in the cylindrical still 1 is heated internally by the relatively hot stream of oil passing from the pipe coil, it is not necessary to subject the bottom of the large still to the high temperature usually employed when all of the heat is transmitted directly to the still bottom.

The pipe coil is preferably provided with an intake pipe 40 having branches 41 and 42 for the admission of steam and natural gas. Valves 43 and 44 may be regulated to control the flow of steam and natural gas, and when necessary or desirable these valves can be closed, or only one of the valves can be opened to admit only one of the fluids to the intake pipe 40. The velocity of the oil in the pipe is increased by introducing the steam and gas at a relatively high pressure. It is important to note that the circulating stream of oil is confined under pressure and cracked in the presence of steam and gas, preferably natural gas. By mixing the steam and gas with the circulating oil, the yield is increased, and a sweeter and better product having a more desirable initial boiling point is obtained. This seems to indicate that only a very small percentage of the oil is converted into a fixed gas, or that the natural gas is absorbed in the oil by the action of steam and a high degree of heat.

The apparatus herein disclosed is claimed in an application filed by me on Sept. 27, 1917, Serial No. 193,457.

I claim:

1. In the art of cracking petroleum hydrocarbons, the method which comprises maintaining hydrocarbon oil in a cracking still and also in another cracking element, forcing a stream of the oil from one of the cracking elements to the other, filtering the stream of oil to separate coke-forming matter therefrom, returning the stream of oil from the last mentioned cracking element to the other, filtering the returning stream of oil to separate coke-forming matter therefrom, heating and vaporizing the oil under pressure, and condensing the vapor.

2. In the art of cracking petroleum hydrocarbons, the method which comprises maintaining a body of oil in a large cylindrical cracking still, continuously discharging a stream of the oil from said cylindrical cracking still, filtering said stream to separate coke-forming matter from the oil, forcing the filtered oil through a pipe coil, filtering the stream discharged from the pipe coil so as to separate coke-forming matter from the oil, then discharging the stream of filtered oil into the large cylindrical cracking still, at the same time heating both the

still and pipe coil, and vaporizing the oil under pressure, and condensing the vapor.

3. In the art of cracking petroleum hydrocarbons, the method which comprises maintaining hydrocarbon oil in a cracking coil and also in a cracking still, forcing a stream of the oil back and forth from one of the cracking elements to the other, heating both cracking elements so as to vaporize the oil under pressure, condensing the vapor, maintaining one of the cracking elements under a higher pressure and at a higher temperature than the other, and regulating the temperature and pressure of each cracking element independently of the other.

4. In the art of cracking petroleum hydrocarbons, the method which comprises maintaining hydrocarbon oil in two cracking apparatus, forcing a stream of the oil back and forth from one cracking apparatus to the other, heating both cracking apparatus so as to vaporize the oil under pressure, maintaining the contents of one cracking apparatus under a higher pressure than the pressure in the other, and condensing the vapor.

5. In the art of cracking petroleum hydrocarbons, the method which comprises maintaining a large cylindrical cracking still in communication with a pipe coil, maintaining a relatively large body of hydrocarbon oil in the cylindrical cracking still, forcibly circulating a stream of the oil from the cylindrical cracking still, through the pipe coil and back into the cylindrical cracking still, heating said still and coil so as to vaporize the oil under pressure, maintaining the contents of the pipe coil under a higher pressure and temperature than the pressure and temperature of the cylindrical still, conducting vapor from the cylindrical still and condensing the vapor.

6. In the art of cracking petroleum hydrocarbons, the method which comprises forcing a stream of hydrocarbon oil from one cracking apparatus to another, maintaining the contents of one of said cracking apparatus at a relatively high temperature and un-

der a relatively high pressure so as to prevent vaporization of the oil therein, maintaining the contents of the other cracking apparatus at a lower temperature and under a relatively low pressure so as to vaporize the oil therein, conducting vapor from the last mentioned cracking apparatus, and condensing the vapor.

7. In the art of cracking petroleum hydrocarbons, the method which comprises maintaining a large cylindrical cracking still in communication with a pipe coil, maintaining a relatively large body of hydrocarbon oil in the cylindrical cracking still, forcing a stream of oil through the pipe coil and into the cylindrical cracking still, heating said still and coil, maintaining the contents of the pipe coil at a relatively high temperature and under a pressure sufficiently high to prevent vaporization of the oil therein, maintaining the cylindrical cracking still at a relatively low temperature and under a relatively low pressure so as to vaporize the oil therein, and condensing the vapor generated in said cylindrical cracking still.

8. In the art of cracking petroleum hydrocarbons, the method which comprises maintaining a large cylindrical cracking still in communication with a pipe coil, maintaining a relatively large body of hydrocarbon oil in the cylindrical cracking still, forcibly circulating a stream of the oil from said cylindrical cracking still, through the pipe coil and then back into the cylindrical cracking still, maintaining the contents of the pipe coil at a relatively high temperature and under a pressure sufficiently high to prevent vaporization of the oil therein, maintaining the cylindrical cracking still at a relatively low temperature and under a relatively low pressure (higher than 50 pounds per square inch) so as to vaporize the oil therein, and condensing the vapor generated in said cylindrical cracking still.

In testimony that I claim the foregoing I hereunto affix my signature.

JOHN W. COAST, JR.
